CONVEYER FRAME STRUCTURE

Frank J. Cozzoli, Plainfield, N. J.

Original application February 2, 1943, Serial No. 475,625. Divided and this application December 20, 1943, Serial No. 514,930

2 Claims. (Cl. 198—204)

1

The present invention relates to machine structures and more particularly to improvements in the structure of base and frame elements whereby the capacity and size of a machine incorporating the invention may be enlarged or decreased to suit a user's needs with a minimum of expense and material.

In my prior application Serial No. 475,625, filed February 2, 1943, of which the present application is a division, a washing machine is disclosed embodying principles of this invention and in the interests of simplicity, that machine will be again referred to as an illustration of the manner in which this invention may be practiced. It will be understood that other and different types of machines may be constructed in a similar manner each possessing the advantages of inexpensive initial cost and variability of capacity and size.

In the washing machine referred to, the main framing of the machine is adapted to receive and support the conveyor mechanisms and the washing instrumentalities, the loading and discharge mechanisms, the drive mechanisms and the controls and is so constituted that the loading mechanism may be eliminated or another substituted and the machine as a whole correspondingly shortened or modified without severe alteration to the main frame structure. In a like respect, the machine's production capacity may be varied by increasing or decreasing the washing units, without severe change in the elements making up the main base and framing.

With the aid of the present invention it becomes possible not only to construct a complete machine relatively inexpensively but to adapt the construction to the individual needs and requirements of the customer. Should the customer's requirements change, the machine originally constructed may, at small cost, likewise be changed to suit the new conditions.

A further aim of this invention is to render available a machine frame construction unit which, by using several, may be used to form bearing elements and sides upon which the moving parts and other elements of the machine may be supported. As an additional refinement, the invention undertakes to provide a structural unit that is inherently strong and so proportioned in size that several may be used side-by-side or one above the other to form rigid sides or columns for the mounting of various machine elements.

Still another aim of the invention is to render available a simple form of structural unit for

2

machine construction, each capable of being easily machined, and which in combination with two or more rail members may be utilized to form a frame section of any desired length which, when assembled, has the inherent capacity to withstand extremely heavy stresses without yielding or fracturing and to resist such twisting or distorting forces that may arise subsequently.

In attaining the aims of the invention it is proposed to connect two leg standards or other supports of suitable height across their tops with a rail section whose length equals the length of the intended machine. Upon the rails are mounted one or more generally rectangular and heavily ribbed bearing plates and to the top of the plates another rail member is securely fastened. The structure thereby formed, provides a sturdy side wall for the machine in which the bearing plates perform not only a construction function but also a means in which shaft journals, etc., may be provided. To suit the characteristics of the machine the bearing plates may be spaced closely or apart along the rails without a loss in the rigidity inherent in the rectangular structure so constituted. The opposite side, and ends when necessary, may be similarly constituted of spaced rails and intervening structural bearing plates, whereby the side walls of the machine is formed to the required length and depth, providing a space between walls of ample capacity for the working parts and mechanisms of the machine.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which—

Figure 1 is a side view of a washing machine embodying this invention.

Fig. 2 is an end view thereof partly in section, better to illustrate the capacity of the new frame structure to accommodate and support machine elements and related mechanisms.

Fig. 3 is a perspective view of a typical frame structure.

Fig. 4 is a perspective view of a wall section assembly.

Fig. 5 is a view of a single construction unit.

Referring to the drawings, the machine illustrated is an ampule washing machine in which the loading and discharge mechanisms forming a part thereof are arranged at a convenient height from the floor for easy control and operation and to suit other equipment. In this instance the height of the machine is determined by the height of the leg standards 10 and the bearing plate units 15, 16, 17, 18 rising therefrom. Each of the leg standards 10 preferably consists of a one-piece casting of box like construction, as illustrated in Fig. 2, which forms a front and a rear leg for each end of the machine. A pair of rail members 11 and 12 are firmly bolted or otherwise secured to the relatively wide top surfaces of the leg standards and by means of which the legs are maintained the selected distance apart and held against rocking out of vertical and against twisting from front to back. The portions of the rails 11 and 12 that extend beyond the leg standards, if unused, may later be cut off.

The rails 11 and 12 are constructed preferably of steel stock to impart strength and rigidity and are generally flat with relatively wide upper and lower bearing surfaces. On top of the rails are mounted bearing plate units 15-18, each of which is substantially rectangular, transversely ribbed as at r and affording bearing areas a, b, and c of generous size along its upper and lower flanged edges and also on one side. The upper ends of the bearing plate units are secured to and support additional rail members 13 and 14. The upper and lower rail members, together with the intervening box-like units 15 etc, thereby forming a self-sustaining wall section, illustrated more clearly in Fig. 4, capable of withstanding heavy loads and stresses that may be imposed thereon. The construction is such that by using increased or decreased lengths of rails, and adding or removing bearing units 15-18, the length of the machine may be altered and the capacity of any specific machine changed to suit requirements without expensive reconstruction.

In the frame shown in Fig. 2, the side walls formed by the plates and rails provide a U-shaped structure, closed at its ends across the bottom and open along the top, (Fig. 3) within and upon which the moving and stationary elements of the machine may be mounted. The ampule washing machine with its conveyor structure shown in the drawings is representative of a machine in which a U-shaped frame structure of changeable length may advantageously be employed, and will now be briefly described.

The conveyor mechanism that supports the washing spindles 42, travels between the planes of the side walls of the frame and includes two linked chain structures 19 and 20, whose pivot rolls 21 engage notches 22 in driving and driven pairs of star wheels 23 and 24. The wheels 23 and 24 are fixedly mounted to shafts 25 and 26, respectively, and these are journaled in bearing blocks 27 and 28 supported by the rails of the main frame. Between the pair of star wheels 23 a ratchet wheel 29 is fixed and adapted to be driven intermittently by means of a spring pressed pawl 30 mounted to the end of an actuating lever 31. The other end of the lever is pivoted to a cross support carried by the rails 13 and 14 at 32 in such a position that a central portion of the lever overlays an actuating cam or roller 33 mounted upon a main cam shaft 34.

A motor 35 mounted to bearing plate 16 drives the main shaft through reduction gearing in a 75

housing 36, and when operating, the actuating arm 31 is caused to be raised and lowered once during each complete turn of the cam shaft. Each time the arm is lifted the pawl 30 engages 5 a notch in the ratchet wheel and indexes the wheel one position. Such movements, it will be seen, advances the conveyor step by step in a counterclockwise direction (in Fig. 1), leaving a dwell period between steps for loading and 10 cleansing operations.

The links of the two conveyor chains are disposed directly opposite one another and are bridged by removable needle trough assemblies 40 each of which comprises an open ended trough 15 member 41 having a plurality of aligned tube supporting hollow needles 42 radiating therefrom. Each needle is screw threaded to the bottom of a trough and its interior arranged to communicate with a common conduit 43 formed in the trough 20 bottom. The conduit is closed at one end and its other end is provided with a valve seat 44 which is adapted to cooperate intermittently with the valved end of fluid supply conduits 45.

In the present embodiment, eight supply stations and eight supply nozzles 45 have been illustrated. The number may, however, be increased or decreased as desired merely by varying the number of conveyor links and adjusting the wheel pivots along the rails accordingly. Each of the 30 nozzles 45 is normally spring pressed toward the valve seat 44 in a related trough assembly by a spring 46 operating between a loose collar 47 and a normally tight collar 48. By adjusting the tight collar to the left (in Fig. 2) the particular nozzle 35 effected may be prevented from moving.

The several nozzles are actuated outwardly by means of levers 49 that are secured to an oscillatable shaft 50 journaled in brackets 51 secured to the framing. Another lever 52 is also secured 40 to the shaft 50 and has its lower end pivotally connected to one arm of a bell crank lever 53 which in turn is pivoted at 54 in a bracket secured to the framing. The other end of the bell crank 53 carries a roller 55 that tracks on the periphery of a cam 56 secured to the cam shaft 34. Part of the surface of the cam 56 is relieved to provide a low portion into which the roller 55 drops during the movement of the conveyor. When the conveyor and the trough assemblies 40 have been indexed, the high portion of the cam 56 engages the roller 55 and actuates the bell crank clockwise from the position illustrated in Fig. 2. This movement through the toggle-like connection with lever 52 rocks the shaft 50 and levers 49 in a counterclockwise direction and the supply nozzles move inwardly and seat upon the respective valve seats in the trough assemblies.

After the nozzles are seated, a valve 60 associated with each supply line, is opened and fluid is directed through one or more of the lines 61, nozzles 45, and conduits 43 of the trough assemblies 40. Normally the valves 60 are closed, and are opened only when their respective valve stems 62 are depressed.

The means for opening the valves comprises a series of adjustable screws 63 carried at the free end of a pivoted bracket 64, each of which may be set so as to effect opening of its related valve to a greater or lesser extent depending upon requirements. The inner end of the bracket is pivoted to the framing, and carries an actuating arm member 65. The arm 65 mounts near its lower end, a roller 66 that engages a cam 67 mounted on the cam shaft. The cam 67 pro-

gresses from minimum to maximum diameter (see Fig. 2) so that the valves are gradually opened and quickly closed.

The valve actuating arm 65 also, during a certain portion of its travel, operates the plunger of a sensitive switch 71 which is normally open and is connected to the drive motor in parallel with a manually operated normally open switch 72. When the operator actuates the switch 72 to a closed position, the motor 35 operates to drive the cam shaft 34 and the parts connected therewith, of which the valve actuating and switch control arm 65 is one. The cam shaft will make approximately one-quarter of a turn before the end 69 engages the plunger 70 and closes the switch 71. When this occurs the operator may release switch 72. Power operation continues until the cam roller 66 rides off the high part of the cam 67. At this point the valve actuating screws 63 are quickly lifted, allowing the valves to close, and the stem 69 lifts away from the switch plunger 70 and the switch 71 opens. The drive motor thereupon stops and the machine comes to rest with all valves closed; and with the loading mechanism retracted to a position ready to receive tubes. Spring elements 73, 74 and 75 assist in the retracting movements of the several elements.

Cooperatively related with the indexing of the troughs is the operation of the loading mechanism, illustrated more particularly in Fig. 1, whose function is to position the unclean ampoules or tubes on the several needles of successive trough assemblies during the time they are at rest. Advantageously, a horizontal position of the needles, as illustrated in these figures, is selected as the loading station. The loading mechanism may comprise a reciprocable carrier 80 that is guided on the rails 13 and 14 and actuated toward and away from the needles by mechanism driven from the common cam shaft 34. A cam element 81 having a gently rising side and a relatively steep side, is mounted upon the cam shaft 34 for that purpose and engages a roller 82 carried by a pivoted lever 83. The lower end of lever 83 connects with generally horizontal link member 84 which in turn connects with the lower end of a pivoted lever 85. The upper end of the lever 85a has a pin and slot engagement with the under side of the carrier 80, and as the main cam shaft rotates, the loading mechanism is reciprocated in timed relation with the conveyor movements. A heavy spring 86 normally tends to urge the roller 82 against the cam 81 and the feed carrier 80 to retracted position.

As illustrated in the drawings, each trough assembly carries six needles whereby six ampoules or tubes may be loaded and subsequently washed simultaneously. Likewise in the tube carrier 89 there are six channels 86 into which unclean tubes are to be laid. The feeding and aligning of the ampoules with the needles is effected mechanically by the overtaking action of the individual plungers 88 which urge the respective tubes into the polished cone shaped recesses 89 provided in centering fingers 90. The centering fingers 90 move forward with the carrier 80 and are provided with similar cone cavities 91 in their sides facing the needles. Thus as the carrier advances, the several needles, should any be not perfectly straight, are guided by the cone walls 91 through a central opening 91a therein and into the ampoule or tube that is centered in the cone on the other side.

The means for advancing the plungers 88 rela-

tive to the carrier is illustrated in Fig. 1 and comprises a sliding frame 100 that is guided on rods 101 that form part of the traveling carrier 80. The carrier also mounts at its rear portion, a pair of supporting rollers 102 rotatably mounted on a shaft 103. Each roller bears upon a track plate 104 secured to the main framing. The shaft 103 pivotally mounts a short lever 105 which has a pin and slot connection with the underside of the sliding frame 100, and by means of a rod-like extension 106, extends through an aperture 107 in a stationary crossplate member 108. Accordingly, as the carrier 90 moves forward, from the position illustrated in Fig. 1, the rod 106 fulcrums on the sides of the opening in the crossplate and rocks the lever 105, and the movement of the lever 105 is transmitted to the slide 100 and plungers 88 secured thereto, whereby the latter move forward slightly faster than the forward movement of the carrier.

As illustrated in Figs. 1 and 2, the ampoules or tubes are prevented from being blown off the needles when the pressure is applied, by a vertically adjustable cover 114. This cover is open ended and normally is set to clear the bottoms of the inverted tubes without allowing the tubes too much end play therebetween.

At the completion of the several cleaning cycles the sterile tubes are carried from under the cover 114 and removed or discharged from the needles. In the embodiment illustrated herein an adjustable guide plate or chute 115 is provided on which the tubes are laid as the needles reach a position below the horizontal. When this occurs the sterile tubes automatically slide off the needles onto the chute and thence onto a conveyor belt 116. The link connection 117 and pin and recesses 118 afford means for adjusting the chute to different tube sizes.

As above indicated the surfaces of the rail members 11-14 are finished smooth and parallel so that when necessary, selected pairs may be used as guides for reciprocable mechanisms, such as for example, the loading mechanism of the machine shown. Also the flanged edges a, b, and at least one side c of the bearing plate members 15-18 are finished smooth and square not only to obtain uniformity in size but to provide finished surfaces on which other elements such as brackets, journal bearings, pivots, etc., may be mounted with precision location and operation. The plates may in a given machine, be turned on their sides or at angles to each other, or cut into smaller width units, as may be desired to suit the machine framing plan. By employing the unit principle herein proposed the need for complicated patterns and castings and machining facilities for large pieces becomes unnecessary.

The flanged upper and lower edges a and b of the bearing plate units are of a depth preferably many times the thickness of the ordinary wall of a base casting which is ample to prevent a tipping of the planes of the side walls. In the present illustration of the invention the depth of the flanges is approximately $\frac{1}{5}$ the width or height of the unit. Additional cross bracing is however provided by the cross members of the machine assembled thereon, such as, in the present instance, by shafts 25, 26, and 34.

The bearing units may be doweled and bolted to the rails, and the rails to the wide surfaces d of the leg standards and thus each member of the box-like assembly assists in supporting the

other members and the entire assembly is braced and held true in all directions.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such 10 adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A supporting structure for a conveyor comprising a pair of leg standards, each of said standards comprising two spaced legs connected at their upper ends, a pair of supporting rails of a selected length secured in parallel spaced relation to the upper portions of said standards and transversely thereto as to form in plan view a generally rectangular structure; a plurality of bearing plate members rising from said supporting rails and connected thereto opposite one another in selected adjusted positions, a second pair of supporting rails secured in parallel spaced relation to the tops of said bearing plate members, said opposite bearing plates, pairs of rails and upper portions of the leg standards forming a machine structure of changeable size and generally U-shaped in transverse vertical section adapted to support machine elements thereon and 35 on and between the upstanding walls formed by said bearing plates.

2. The combination set forth in claim 1 in which said rails extend beyond the leg standards at one end, and additional bearing plate members interposed between the extended portions 5 of the rails.

FRANK J. COZZOLI.
